Primary Examiner — Jonathan J Han*Assistant Examiner* — Jeff Lenard D Torres(74) Attorney, Agent, or Firm — Thomas | Horstemeyer, LLP(57) CLAIM

The ornamental design for a shoe, as shown and described.

DESCRIPTION

FIG. 1 is a perspective view of a shoe, showing my new design;

FIG. 2 is a front view thereof;

FIG. 3 is a rear view thereof;

FIG. 4 is a side view thereof;

FIG. 5 is a side view thereof, opposite that of FIG. 4;

FIG. 6 is a top view thereof; and,

FIG. 7 is a bottom view thereof.

The dashed lines on the shoe upper represent stitching and form part of the claimed design.
